UNITED STATES PATENT OFFICE

JAMES WARING CARPENTER, OF PITTSBURGH, PENNSYLVANIA, ASSIGNOR TO THE
McKAY COMPANY, OF PITTSBURGH, PENNSYLVANIA, A CORPORATION OF PENNSYLVANIA

DESIGN FOR A MAGAZINE RACK

Application filed January 21, 1933. Serial No. 46,927. Term of patent 7 years.

To all whom it may concern:

Be it known that I, JAMES WARING CARPENTER, a citizen of the United States, residing at Pittsburgh, in the county of Allegheny, State of Pennsylvania, have invented a new, original, and ornamental Design for a Magazine Rack, of which the following is a specification, reference being had to the accompanying drawing, forming a part hereof.

Figure 1 is a face view of a magazine rack embodying my new design; Fig. 2 is an end view thereof, and Fig. 3 is a fragmentary plan view of the magazine rack of Fig. 1.

I claim:

The ornamental design for a magazine rack, as shown.

JAMES WARING CARPENTER.
